UNITED STATES PATENT OFFICE.

VICTOR CLIFFORD, OF TULSA, OKLAHOMA, ASSIGNOR TO PETROLEUM SAFETY APPLI-
ANCE COMPANY, OF TULSA, OKLAHOMA, A CORPORATION.

VENT FOR LIQUID CONTAINERS.

Application filed August 25, 1922. Serial No. 584,373.

To all whom it may concern:

Be it known that I, VICTOR CLIFFORD, a citizen of the United States, residing at Tulsa, in the county of Tulsa and State of Oklahoma, have invented new and useful Improvements in Vents for Liquid Containers, of which the following is a specification.

This invention relates to vents of the kind that are used on liquid containers.

10 The main object of my invention is to provide a vent for liquid containers which is so constructed that it will prevent evaporation of the liquid in the container on which it is used, permit air to enter the container to facilitate the withdrawal of the liquid therefrom, and automatically relieve an abnormal internal pressure in the container.

Another object is to provide a vent of the 20 character above described that will protect the contents of the container from fire, that is reliable in operation and which is inexpensive to build and install.

To this end I have devised a vent which is 25 provided with a liquid sealed inlet valve and a liquid sealed outlet valve arranged in such a manner that they normally cut off communication between the atmosphere and the interior of the liquid container on which 30 the vent is used, but are capable of operating automatically to permit air to enter the container when liquid is being withdrawn from the container and to permit gases to escape from the container when an 35 abnormal pressure is created in the container. The vent preferably comprises a hollow member provided with two reservoirs for holding liquid, an inlet valve and an outlet valve associated with said reservoirs and sealed by the liquid in same, and an opening in said hollow member arranged in such a way that the operation of withdrawing liquid from the container causes air to pass through said opening and unseat 40 the inlet valve, and the accumulation of an abnormal quantity of gases in the container causes the outlet valve to unseat and permit the gases to escape through said opening, thereby relieving the internal pressure in 45 the container.

A vent of the construction above described is capable of use with various kinds of liquid containers, but it is particularly adapted for use on containers in which hydrocarbons 50 are stored or transported, as it eliminates

evaporation, effectively protects the contents of the container from fire and overcomes the necessity of manually opening an air valve when the liquid is being withdrawn from the container.

50 Figure 1 is a longitudinal sectional view of a vent constructed in accordance with my invention.

Figure 2 is a side elevation, showing it arranged in operative position on a liquid 55 container; and

Figure 3 is a cross-sectional view, taken on the line 3—3 of Figure 1.

Referring to the drawings, the numeral 10 designates an elongated upstanding casing or hollow member which is preferably cylindrical and which has its upper end closed and its lower end open and formed with a flange 11 that is adapted to be connected to the upper side or top of a container A. At its intermediate portion one side of said casing is provided with an opening 12 surrounded by a flange 13 to which is bolted the flanged end 14 of a conduit member 15. A fine wire screen 16 is held between the flanges 13 and 14 for the purpose of preventing flaring back of flame in case of an explosion. In the form of my invention herein shown the top of the casing 10 is provided with an opening normally closed by a closure plug 17 having an angular wrench engaging head 18. Extending longitudinally of the casing is a passage 19 whose upper end communicates with the interior of the upper portion of said casing 70 and whose lower end communicates with the interior of the container A. 75

Extending transversely of the casing 10 above the opening 12 is a partition 20 having a threaded opening 21 therein into which is screwed the lower end of an upstanding tubular member 22 formed in its opposite sides with openings 23, the annular space surrounding said member 22 constituting a reservoir. Telescopically engaged upon this tubular member 22 is an inverted cup-shaped inlet valve 24 which is normally sealed by a quantity of oil 25 in the reservoir surrounding the tubular member 22, as shown. The oil supply within this reservoir may be replenished through a filling neck 26 having a screw plug 27. Also leading from this reservoir is a drain cock 28 whereby the oil may be removed when desired. 80

100 Located within the lower portion of the 110

casing 10 is a partition 29 having a threaded opening 30 therein into which is screwed an upstanding tubular member 31 formed with openings 32 and normally covered by an inverted cup-shaped outlet valve 33 having its lower end sealed in a body of oil 34 in the reservoir formed by the annular space that surrounds the member 31. I provide said reservoir with a filling member 35 and a drain cock 36 similar to the elements 26 and 28 already described.

Upward movement of the inlet valve 24 is limited by its engagement with the plug 17 while upward movement of the outlet valve 33 is limited by engagement with a stop 37 which extends transversely of the casing at the upper edge of the opening 12 therein.

In the operation of the device it will be seen that in case vapor of various kinds should arise from the container A and pass into the casing 10 and subsequently condense, when the level within either of the two liquid reservoirs exceeds a certain degree, the liquid will overflow through the openings 23 and 32 and pass back into the container A.

If for any reason pressure should accumulate within the container A or the casing 10, the valve 33 will rise and permit the pressure to escape through the openings 32 and thence into the conduit 15. The passage 19 constitutes a vacuum relief through which air is admitted to the container A during the operation of withdrawing liquid from the container, the air entering through the opening 12 and exerting pressure on the inlet valve 24 in a direction to unseat same.

From the foregoing description and a study of the drawings it will be readily apparent that I have thus provided a simply constructed and consequently inexpensive attachment for containers of various kinds and for various purposes which will operate to relieve pressure and prevent the formation of any vacuum within the container, it being well known that such pressure or vacuum formation will naturally have a harmful effect upon the container. It is to be observed that the action of my device is automatic in every way and that it will require absolutely no attention on the part of an operator. Owing to the simplicity of the construction and the fewness of the parts, it is apparent that there is nothing to get out of order and that the device should consequently have a long life and satisfactorily perform all the functions for which it is intended.

While I have shown and described the preferred embodiment of the invention, it is of course to be understood that I reserve the right to make such changes in the form, construction and arrangement of parts as will not depart from the spirit of the invention or the scope of the subjoined claims.

Having thus described my invention I claim:

1. A device of the character described comprising an upright casing designed to be mounted upon a container and provided in one side with an opening, a pair of partitions within said casing above and below said opening, tubular members extending through said partitions and formed with openings and inverted cup-shaped valves extending over said tubular members and having their open ends sealed in a body of liquid on the partitions. 70

2. A device of the character described comprising an upright casing designed to be mounted upon a container and provided in one side with an opening, a pair of partitions within said casing above and below said opening, tubular members extending through said partitions and formed with openings and inverted, cup-shaped valves extending over said tubular members and having their open ends sealed in a body of liquid on the partitions, a filling neck and a drain cock associated with each of said liquid chambers. 80

3. A device of the character described comprising an upright casing designed to be mounted upon a container and provided in one side with an opening, a pair of partitions within said casing above and below said opening, tubular members extending through said partitions and formed with openings, and inverted, cup-shaped valves extending over said tubular members and having their open ends sealed in a body of liquid on the partitions, said casing being formed at one side with a longitudinally extending passage that establishes communication between the upper end of said casing and the container. 85

4. A vent for liquid containers, consisting of a member adapted to be connected to a container and provided with a liquid sealed inlet valve and a liquid sealed outlet valve. 90

5. A vent for liquid containers, provided with a liquid sealed inlet valve and a liquid sealed outlet valve arranged in such a way that the inlet valve will unseat automatically and thus permit air to enter the container during the operation of withdrawing liquid therefrom and the outlet valve will unseat automatically in the event an abnormal pressure is created in the container and thus relieve said pressure. 100

6. A vent for liquid containers, comprising a hollow member adapted to be connected to a container and provided with a liquid sealed inlet valve and a liquid sealed outlet valve, and an opening in said member that is used to admit air to the container under certain conditions and to permit gases to escape from the container under certain conditions. 105

7. A vent for liquid containers, comprising a liquid sealed inlet valve and a liquid sealed outlet valve, means whereby the operation of withdrawing liquid from the container causes air to unseat the inlet valve and travel through a passageway into the container, and a separate passageway leading from the container through which gases can escape and unseat the outlet valve 10 in the event an abnormal pressure is created in the container.

8. A vent for liquid containers, consisting of a hollow member adapted to be connected to a container and provided with 15 an inlet passageway and a discharge passageway, and liquid sealed valves combined with said passageways in such a manner that the operation of withdrawing liquid from the container tends to close the outlet valve and open the inlet valve and the creation of an abnormal pressure in the container tends to open the outlet valve and seat the inlet valve.

9. A vent for liquid containers, comprising 25 a hollow member provided with two liquid reservoirs, an inlet valve sealed by the liquid in one of said reservoirs, an outlet valve sealed by the liquid in the other reservoir, and a combined inlet and outlet 30 opening in said member that co-operates with both of said valves.

10. A vent for liquid containers, com-

prising a hollow member adapted to be mounted on a liquid container in such a way that the lower end of same is in communication with the container, liquid reservoirs in said hollow member arranged one above the other and each equipped with a valve that is normally sealed by the liquid in the reservoir, an opening in said hollow member arranged at a point between said reservoirs for the purpose described, and an air inlet passageway in said hollow member that establishes communication between the upper end of said member and the interior of the container. 35 40 45

11. A vent for liquid containers, comprising a hollow member adapted to be mounted on a container and provided at its lower end with an opening which establishes communication between the container and the lower portion of said member, an air passageway in said member that establishes communication between the container and the upper end portion of said member, an opening in the intermediate portion of said member through which air can enter said member or gases can escape from said member, and liquid sealed valves arranged above and below said opening, 50 55 60 for the purpose described.

In testimony whereof I affix my signature.

VICTOR CLIFFORD.
